PRESSURE-EXERTING TOOL

Application filed November 7, 1927. Serial No. 231,458.

This invention relates, generally, to a tool for exerting, at the will of the user, either pushing or pulling pressure, to perform such operations as the setting up of slidable elements on supporting rods, shafts, or the like, when it is required to forcibly move said elements into a desired operative position, or to pull rods, shafts or the like from their settings, or for any similar work wherein the exertion of either pushing or pulling force is required.

The invention has reference, more particularly, to a novel pressure exerting tool for use in setting up or forcing home the clamp-collars of tie-rods employed in binding concrete form walls in operative assembled relation, or for use in pulling tie-rods and the like out of concrete, etc., when dismantling forms.

The present invention has for its principal object to provide a simple and easily actuated construction of pressure exerting tool for general use and for the special uses above referred to, which comprises, broadly, a thrust-block or sleeve, a gripping means adapted to be temporarily locked on a tie-rod, shaft or the like, and a power exerting lever interconnected between said thrust block or sleeve and said gripping means.

Other objects of this invention, not at this time more particularly enumerated, will be clearly understood from the following detailed description of the same.

The present invention is illustrated in the accompanying drawings, in which:—

Figure 1 is a transverse vertical section through a concrete form showing a tie-rod extending therethrough to bind the side walls of the form in assembled relation, said tie-rod having a clamp-collar thereon, and one form of the novel tool embodying the principles of the present invention being shown in side elevation in operative relation to the tie-rod and clamp-collar ready for manipulation to set up the latter; Figure 2 is a similar view, but with parts of the tool in longitudinal section, and Figure 3 is a top plan view of the tool as shown in Figure 1.

Figure 4 is a view similar to that shown in Figure 1 but illustrating a modified form and construction of pressure exerting embodying

the principles of this invention, and Figure 5 is a top plan view of the same.

Similar characters of reference are employed in the hereinabove described views, to indicate corresponding parts.

Referring first to the type of tool construction illustrated in Figures 1 to 3 inclusive, the reference character 6 indicates the side walls of a concrete form and 7 a tie-rod extending therethrough to secure the same in operative assembled relation. One end of the tie-rod is provided with a nut 8 to form a stop to engage the tie-rod with a wall 6 at one side of the form. The opposite end 7' of the tie-rod extends in outward projection beyond the exterior face of the wall 6 at the other side of the form. Slidably disposed on the free end portion 7' of said tie-rod is a clamp-collar 9, preferably provided at its inner end with a flange 10 to furnish a broad bearing for engagement with the adjacent side wall 6 of the form. Said clamp-collar is preferably provided with set-screws 11 threaded into and through opposite sides thereof, as shown in Figure 3. The clamp-collar, in practice, is forced tightly home on the tie-rod to abut the exterior face of the adjacent wall of the concrete form, whereupon the set-screws 11 are turned into biting engagement with the tie-rod to retain the clamp-collar in operative holding relation to said form wall. The tool of the instant invention serves to apply the required force to the clamp-collar to tightly set up the same, and at the same time draw the tie-rod so as to also set up the stop-nut 8 in tight holding relation to the opposite form wall.

The novel tool of this invention comprises a thrust block 12 preferably in the form of a sleeve having a longitudinal bore 13 to receive the free end 7' of the tie-rod, whereby the block or sleeve may be positioned behind the clamp-collar 9 to be set up. Said block or sleeve 12 is provided with an exterior perforate ear or lug 12'. The reference character 14 indicates a gripping block also provided with an opening 15 to receive the free end 7' of the tie-rod so that the gripping block may be fixed on the tie-rod behind the thrust block or sleeve 12. Said gripping

block 14 is provided at its upper end portion with a forwardly extending fulcrum arm 16 which is preferably integrally formed therewith; and extending rearwardly from said gripping block is a handle extension 17. Said gripping block is further provided, preferably in connection with its lower end portion, with a pair of perforate bearing members 18 to hold a cross-pin 18' to pivotally mount an eccentric locking cam 19 having a manipulating handle member 20. Said locking cam 19 is arranged to enter sidewise into the bore or opening 15 of the gripping block and so as to be engageable with the tie-rod extending through the latter, whereby, at will, the gripping block may be immovably locked to the tie-rod in stationary relation thereto. The biting face of said locking cam 19 may be provided with teeth 21 if desired to increase the frictional holding engagement thereof with the tie-rod. The reference character 22 indicates a power-exerting lever member provided at its lower end with a bifurcated portion to receive the fulcrum arm 16 of the gripping block to which pivotal connection is made by the fulcrum pin or bolt 23. The lower end of said power exerting lever 22 is pivotally connected with the perforate ear 12' of the thrust block or sleeve 12 by a pivot pin or bolt 24. Extending upwardly from the upper end of said lever member 22 is a suitable lever handle 25.

In operating the form of tool above described to set up a clamp-collar on the tie-rod in tight holding engagement with a form wall, the thrust block or sleeve 12 and gripping block 14 are slid upon the tie-rod to position the thrust sleeve behind the clamp-collar, and the gripping block 14 is moved to a position which will cant forward the lever member 22 and its handle, whereupon the gripping block 14 is locked to the tie-rod so as to provide a purchase for the operation of the lever member to produce thrusting movement of the thrust block or sleeve 12. When the tool, with its parts thus initially disposed, is in place, the operator grasps and pulls upwardly on the handle 17 and grasps and swings rearwardly the lever handle 25 to turn the lever member 22 on its fulcrum pin or bolt 23. By such operation the lower end of the lever member 22 is swung forward thereby exerting a powerful forward thrusting movement of the thrust block or sleeve 12 against the clamp-collar with the double effect of both drawing the tie-rod 7 outwardly to tightly seat the stop-nut 8 against one wall of the form while at the same time sliding tightly home the clamp-collar 9 against the other wall of the form; at the same time the upwardly pulling pressure exerted on the handle 17 counteracts downward pressure on the tie-rod, which might otherwise tend to bend

the same. By properly positioning the parts of the tool on the tie-rod, the lever handle 25 may be drawn or swung back substantially parallel to the handle extension 17 of the gripping block 14, so that the operator may grasp both such parts with one hand to thus hold the tool in clamp-collar setting position, and so that one hand of the operator remains free to manipulate the set-screws 11 to lock said clamp-collar in the operative set up position to which it has been moved by the described manipulation of the tool. It may be desirable to furnish the tool with mechanical means for holding the same in pressure exerting position. One form of mechanical means adopted to such purpose is also illustrated in Figures 1 to 3 of the drawings, and consists in a notched quadrant 26 suitably secured to the gripping block 14 to lie adjacent to the path of operative movement of said lever member 22, and the latter member is provided on a side adjacent to said quadrant with a pivoted detent pawl 27 to engage the notches of said quadrant whereby the lever member 22 is retained in the operative position to which it may have been moved. Variations of such mechanical holding means may be employed as will be understood, and the same may be omitted entirely when desired under the broader aspects of this invention.

The tool as above described may be utilized in practice to exert pulling pressure on the tie-rod when dismantling a form subsequent to the pouring of the concrete structure for which the form is designed. When making such use of the tool, the gripping block 14 is locked on the tie-rod with the thrust block or sleeve 12 abutting the clamp-collar 9. The set-screws 11 of the clamp-collar are relaxed to release the latter relative to the tie-rod, and the stop-nut 8 is removed from the opposite end of said tie-rod. When the parts are thus prepared and adjusted, the operator pulls rearward the lever member 22 by means of a lever handle 25, thereby causing the thrust block or sleeve to thrust against the immovable clamp-collar for purchase while at the same time the swing of the lever member 22 transmits an outward pulling pressure to the tie-rod through the gripping block 14, thus withdrawing or pulling out the latter from the concrete. These operations may be repeated to effect a step by step withdrawing movement of the tie-rod, as will be obvious.

Referring now to Figures 4 and 5 of the drawings, I have shown therein a somewhat modified form of tool which embodies, however, the general principles of construction and mode of operation upon which the present invention is based.

In this modified construction I provide a thrust block or sleeve 28 having a longitudinal bore to receive the tie-rod end 7' and al-

so having a perforate lug or ear 29. The gripping block is in the form of a sleeve or collar 30 also provided with a bore to receive the tie-rod end, and having in operative connection therewith the pivoted eccentric locking cam 31 for temporarily locking the gripping block to the tie-rod. The lever member 32 is pivotally connected with the forward end of the gripping block by means of 5 links 33, which have their forward ends respectively disposed on opposite sides of the lever member, and operatively connected with the latter by a fulcrum pin or bolt 34 while their rearward ends are pivotally connected 10 with the gripping block by a pivot pin 35. The rearward end of one of said links 33 may be rearwardly extended to provide a handle extension 36. The lower end of said lever member 32 is pivotally connected 15 with the perforate ear 29 of said sleeve 28 by a pivot pin or bolt 37, and said lever member 32 is also provided with an upwardly extending lever handle 38 for actuating the same. In general the manner of operating 20 and using the above described modified form of tool is substantially the same as above set forth in connection with the first described construction, both to produce pushing or pulling pressures.

30 The novel forms of pressure exerting tool hereinabove described provide very effective means for purposes in view, and in operation so distribute the strains consequent upon their operation that risk of bending the tie- 35 rods or otherwise producing distortion thereof is eliminated, while at the same time permitting the exercise of required force necessary to the results sought.

While I have shown in the accompanying 40 drawings and described in the foregoing specification, as well as pointed out in the annexed claims, certain novel features of the present invention, it will be understood that various omissions, substitutions and changes 45 in forms and details of the devices illustrated and described may be made without departing from the spirit of the invention as comprised within the terms of the appended claims.

50 I claim:

1. A pressure exerting device for use in connection with rods and fittings mounted thereon, comprising a thrust block slidable on the rod, a gripping block receivable on 55 the rod, said gripping block having a rearwardly projecting handle extension for exerting upward pressure on the rod during manipulation of the device, means to lock said gripping block to the rod, and a power 60 exerting lever member having a lever handle at one end, means to fulcrum said lever member on said gripping block, and means for pivotally connecting the opposite end of 65 said lever member with said thrust block.

65 2. A pressure exerting device for use in

connection with rods and fittings mounted thereon, comprising a thrust block slidable on the rod, a gripping block receivable on the rod, said gripping block having a pivoted eccentric locking cam to lock the same to the rod, and a power exerting lever member pivotally connected with said gripping block and having an end thereof pivotally coupled with said thrust block. 70

3. A pressure exerting device for use in connection with rods and fittings mounted thereon, comprising a thrust block slidable on the rod, a gripping block receivable on the rod, said gripping block having a pivoted eccentric locking cam to lock the same to the rod, a fulcrum arm projecting forwardly from said gripping block, a power exerting lever member pivoted on said fulcrum arm, means for pivotally connecting an end of said lever member with said thrust block, 75 and a lever handle extending from the opposite end of said lever member. 80

4. A pressure exerting device for use in connection with rods and fittings mounted thereon, comprising a thrust block slidable on the rod, a gripping block receivable on the rod, said gripping block having a pivoted eccentric locking cam to lock the same to the rod, a fulcrum arm projecting forwardly from said gripping block, said gripping 90 block having a rearwardly projecting handle extension, a power exerting lever member pivoted on said fulcrum arm, means pivotally connecting an end of said lever member with said thrust block, and a lever handle extending from the opposite end of said lever member. 100

In testimony that I claim the invention set forth above I have hereunto set my hand this 4th day of November, 1927. 105
